ADON J. HOFFMAN, OF SYRACUSE, NEW YORK

PRESSING ELEMENT FOR GARMENT-PRESSING MACHINES

Application filed August 16, 1927. Serial No. 213,300.

This invention relates to a pressing element for garment pressing machines in which the press-head and buck are elongated horizontally and the press-head is movable vertically about an axis parallel with the longitudinal center of the buck, as commonly used in tailor shops, clothing establishments, laundries and similar places, for steaming, sterilizing, pressing and shaping the garment in substantially one continuous operation.

In the installation of machines of this character in tailor shops and other small places, it is customary to provide a small steam boiler having a gas-heater for converting the water into steam for direct delivery to the press-head or buck for steaming purposes, thereby adding greatly to the initial cost of installation and expense of maintenance in addition to the inconveniences arising from excess heat and escape of steam through leakages or over-supply in the room in which the machine is located.

The main object of the present invention is to reduce to a minimum the initial cost of installation and maintenance, and also to avoid as far as possible the inconveniences and unsanitary conditions arising from the escape of steam into the room by converting the water into steam wholly within the pressing element from which the steam or moist vapor is to be delivered to the garment.

One of the specific objects is to provide the pressing element with an electrically-heated chamber interposed between the moisture-receiving chamber and the steam distributing chamber in such manner that the walls of the heating chamber will convert the water into steam or vapor, and also superheat the steam or vapor as it is delivered or distributed to the garment, and thereby to accomplish two important results, viz: the reduction of the moisture content of the steam or vapor and the resultant quick drying of the garment immediately following the pressing operation.

Another object is to provide the distributing chamber with a flexible foraminous press-plate, and to support said press-plate by resilient connections between the marginal edges thereof, and main body of the press-

ing element, so that during the pressing operation, the steam or vapor partially entrapped in the distributing chamber will be forced through the foramina of the plate to the garment as the plate is collapsed toward the main body by pressure upon said garment.

A further object is to connect the distributing chamber to the moisture-receiving chamber by a suitable port, and to control the passage of the vapor from the receiving chamber to the distributing chamber by means of a manually-operated valve.

Another object is to provide the pressure side of the heating chamber with an imperforate plate having channels in its pressure-face radiating from the port to the marginal edges thereof to allow the steam or vapor to radiate from said port to all portions of a flexible pressing plate when the latter is pressed toward or against the press-plate of the heating chamber.

Other objects and uses relating to the specific use of the device will be brought out in the following description:

In the drawings,

Figure 1 is a side elevation of a press-head of a garment pressing machine.

Figure 2 is a horizontal sectional view of the same head through the heating chamber showing the electric heating elements taken on the plane of line 2-2, Figure 4.

Figure 3 is a horizontal sectional view taken in the plane of line 3-3, Figure 4.

Figure 4 is an enlarged transverse vertical sectional view taken in the plane of line 4-4, Figure 1.

As illustrated, this press-head comprises a hollow casting —1— having a moisture-receiving chamber —2— and a heating chamber —3—, both extending longitudinally and laterally throughout substantially the entire area of the head, the heating chamber —3— being made in the form of a recess in the bottom of the casting —1—.

A presser-plate —4— is secured along its marginal edges to the corresponding marginal edges of the casting —1— by screws —5—, or equivalent fastening means, whereby the plate —4— may be removed when

desired to facilitate the installation and removal of suitable electric-heating elements —6.

A foraminous presser-plate —7— of flexible material is provided with marginal flanges —8— having their marginal edges shirred or otherwise secured to a marginal flange —9— on the casting —1— to permit the removal and replacement of the plate —7— when desired, the flanges —8— being of sufficient vertical height to support the plate —7— in spaced relation to the plate —4— to form an intervening distributing chamber —10—, as shown in Figure 4.

Suitable means is provided for distending the flanges —8— and yieldingly holding the plate —7— in spaced relation to the plate —4—, said means consisting in this instance of a longitudinally corrugated spring wire —11— extending around the flange —8— and attached thereto at intervals by suitable fastening devices 12, as shown more clearly in Figure 1.

The heating units —6— are preferably made in the form of cartridges removably inserted in the heating-chamber —8—, and normally held in operative position between the plate —4— and the dividing partition, as 1' between the chambers —2— and —3—. If desired, a thin lining 13 of asbestos or equivalent material may be applied to the lower surface of the partition 1' adjacent the heating element —6— to expedite the initial heating of the plate —4— while permitting the transfer of heat to the plate —1'— to a degree sufficient to vaporize the moisture in the chamber —2—.

The partition 1' is provided with a substantially central hollow boss 14 extending therefrom toward the plate —4— and threaded internally for receiving a tubular bushing 15, which together with the boss 14 constitutes a port 16 connecting the moisture-receiving chamber —2— with the distributing chamber 10.

The bushing 15 extends into a central opening 17 in the plate —4—, and is provided with a tapered valve-seat 18 adapted to be engaged by a tapered valve —19—, preferably for the self-closing type, adapted to open toward the distributing chamber —10—. The valve —19— is provided with a stem —20— extending through a suitable gland —21— in the outer wall of the chamber —2— and adapted to be engaged by a hand-lever —22— which is pivoted at —23— to a portion of the gland —21—, as shown in Figure 4.

A spring —24— is mounted in a suitable chamber in the gland —21— to engage one end of said chamber, and a shoulder —25— on the stem for yieldingly holding the valve —19— in closed position, and permitting it to be opened by depression of the hand-lever —22—.

The face of the plate —4— adjacent the flexible presser-plate —7— is provided with channels —26— radiating from the adjacent end of the port —16— to various portions of the marginal edges of said plate to allow the distribution of the steam or vapor throughout practically the entire area of the distributing chamber —10—, even when the press-plate —7— is pressed against the adjacent side of the plate —4—, resulting in a uniform distribution of the vapor or steam over the entire area of the garment covered by the flexible presser-plate —7—.

This presser-plate —7— is preferably laminated, and comprises an inner layer —27— of woven wire fabric, and an outer layer —28— of cloth fabric resting one against the other, the flanges —8— forming extensions of the cloth fabric —28— so that when the marginal edges of said flanges are attached to the flanges —9— of the casting —1—, a pocket is formed for receiving and retaining the woven wire fabric layer —27— in operative position.

The heating chamber —3— extends across the entire area of and beneath the moisture-receiving chamber —2—, while the distributing chamber —10— extends across the entire area of and beneath the heating chamber. The heating chamber therefore lies between the moisture-receiving chamber —2— and the distributing chamber —10— and serves to vaporize the moisture in the chamber —2— and, when the valve —19— is opened to permit the passage of the steam or vapor from the chamber —2— into the distributing chamber —10—, also serves to superheat the steam or vapor in the distributing chamber, and thereby to reduce the moisture content of the steam applied to the garment for expediting the drying of the garment immediately following the pressing operation.

The moisture-receiving chamber —2— may be connected to any available source of water supply through the medium of a pipe —29— connected to an inlet —30— preferably in the rear side of the casting —1—, as shown in Figure 4. The pipe 29 may be provided with any suitable valve, not shown, adapted to be opened only when the valve 19 is closed and then just long enough to permit a small quantity of the water to pass into the chamber 2 for instant conversion into steam by the underlying heated wall 1'. If, however, any slight amount of water should be present in the port 16 when the valve 19 is opened it would be sprayed into the distributing chamber 10 by reason of the tapered form of the valve and underlying screen 31 without detriment to the garment.

A metallic screen —31— is secured to the plate —4— across the adjacent end of the port —16—, or between the valve —19— and flexible plate —7— to cooperate with the valve in breaking up or atomizing the mois-

tened vapor, as it passes from the chamber —2— to the distributing chamber —10—.

As previously stated the flexible foraminous press plate —7— is yieldingly held in spaced relation to the lower face of the overlying plate —4— to form the steam-distributing chamber —10— so that during the pressing operation the steam or vapor partially entrapped in said chamber will be forced through the foraminous plate —7— as the latter yields toward the plate —4— by pressure upon the garment thereby increasing the force of discharge of the steam into the surface of the garment somewhat in proportion to the pressure for moistening purposes.

I claim:

1. In a garment pressing machine, a press-head having lower, upper and intermediate chambers and an enclosed port extending through the lower and upper walls of and across the intermediate chamber and connecting the lower and upper chambers, the lower chamber having a foraminous bottom wall, a valve normally closing said port, means for supplying moisture to the upper chamber, means operable at will for opening said valve, and means within the intermediate chamber for heating the upper and lower walls thereof for vaporizing the moisture in the upper chamber and for superheating the vapor in the lower chamber.

2. In a garment pressing machine, a press-head having lower, upper and intermediate chambers approximately coextensive with the length and breadth of the adjacent portions of the head, said head having an enclosed port extending through the lower and upper walls of and across the intermediate chamber and connecting the lower and upper chambers, a valve controlling said port and normally closing the same, and means operable at will for opening the valve.

3. In a garment pressing machine, a press-head having lower, upper and intermediate chambers approximately coextensive with the length and breadth of the adjacent portions of the head, said head having an enclosed port extending through the lower and upper walls of and across the intermediate chamber and connecting the lower and upper chambers, a valve controlling said port and normally closing the same, means operable at will for opening the valve, means within the intermediate chamber for heating the walls thereof, means for conducting liquid into the upper chamber for conversion into vapor to be discharged into the lower chamber when the valve is opened, the outer wall of the lower chamber being foraminous to permit the escape of vapor therethrough.

4. In a garment pressing machine, a press head having a steam distributing chamber provided with a relatively rigid top wall and

a flexible foraminous bottom wall, the top wall being provided with a steam inlet port in opposed relation to the bottom wall, a valve controlling said port, and resilient connections between the marginal edges of the foraminous bottom wall and overlying portions of the press head and tensioned to normally hold the bottom wall in spaced relation to the top wall and to permit said bottom wall to move toward the top wall when engaged with the garment under pressure for expelling the steam from the distributing chamber through the foraminous bottom wall when the valve is closed.

5. In a garment pressing machine, a press head having a steam distributing chamber provided with a relatively rigid top wall and a flexible foraminous bottom wall, the top wall being provided with a steam inlet port in opposed relation to the bottom wall, a valve controlling said port, and resilient connections between the marginal edges of the foraminous bottom wall and overlying portions of the press head and tensioned to normally hold the bottom wall in spaced relation to the top wall and to permit said bottom wall to move toward the top wall when engaged with the garment under pressure for expelling the steam from the distributing chamber through the foraminous bottom wall when the valve is closed, said top wall being provided with channels in its underside radiating in different directions from said port to facilitate the spreading out of the steam into said chamber when the valve is opened.

In witness whereof I have hereunto set my hand this 12th day of August, 1927.

ADON J. HOFFMAN.
